United States Patent Office.

HUGH THOMAS AND ROBERT WALLACE, OF NEW YORK, N. Y.

Letters Patent No. 95,165, dated September 21, 1869.

IMPROVED MECHANICAL MOVEMENT.

The Schedule referred to in these Letters Patent and making part of the same

To all whom it may concern:

Be it known that we, HUGH THOMAS and, ROBERT WALLACE, both of the city, county, and State of New York, have invented a new and improved Mechanical Movement; and we do hereby declare that the following is a full, clear, and exact description of the same, reference being had to the accompanying drawing, forming part of this specification, and in which—

Figure 1 is a longitudinal central section of our invention as applied to screw-braces;

Figure 2 is a transverse section on line xx in fig. 3; and

Figure 3 is a horizontal section on the line yy , corresponding to fig. 1.

Similar letters of reference indicate corresponding parts in all the figures.

This invention consists in a novel device for converting oscillating motion into rotary motion, and it is applicable to screw-braces, ratchet-drills, screw-jacks, and all machines in which a ratchet-motion is commonly used.

One of the principal features of this device consists in means whereby it is made reversible by simply turning the handle or operating lever in its socket.

To enable others skilled in the art to construct mechanical movements in accordance with our improvement, we will proceed to describe the same with reference to the drawing.

A is a wheel, of any desirable size, having a suitable number of holes, $a a$, at equal distances from each other, formed on the periphery of the same, and which may be round, or of any other form.

This wheel is arranged within a case, B, and is allowed to rotate therein freely.

The case B is made with a radial extension or socket, B', large enough to receive the rod or lever C, and the spiral spring D.

The rod C passing through the socket B', enters the case B far enough to drop into the holes $a a$ of the wheel A.

A collar, e, keeps the lever C from dropping too far, while the spring D, around said lever, holds it down with sufficient force to insure its being always in gear with the wheel A.

The face d of that end of the lever C which drops

into the holes $a a$, is bevelled, so as to allow the lever to slip out of those holes when moved in one direction, and to rotate the wheel A when moved in the other direction, as clearly shown in fig. 2.

To make it reversible or inoperative, the lever C is further provided with a feather, e, to fit loosely into either of the grooves $f f' f''$ cut into the screw-cap g, and maintain the lever C in a desired position.

The position of lever C, shown in figs. 1 and 3, makes it inoperative, the end of the lever C being unable to slip out of the holes $a a$ when moved in either direction.

To make it rotate the wheel A in the direction of the arrow, as shown in fig. 2, the rod C is raised high enough to free the feather e from the groove, and then turned until the feather e comes in line with the groove f' , when the lever C is dropped, and the feather e, fitting into the groove f' , holds it in position.

The lever C, now receiving an oscillating motion, rotates the wheel A, the straight side of its end acting against the wheel A, while the bevelled side allows it to slip out of the holes $a a$, and bring the straight side again into action.

To rotate the wheel in the opposite direction, the lever C is raised and turned half a revolution, when the feather e will drop into the groove f'' , and the bevelled end of the rod being thereby turned in the opposite direction, reverses the motion.

To transmit the motion of the wheel A, a screw, as shown in the drawing, or other desirable means, may be applied.

What is here claimed, and desired to be secured by Letters Patent, is—

The combination, with the wheel A, of the case B, having a radial extension, B', provided with grooves $f f' f''$, the rod or lever C, fitting to the said socket, and having a bevelled inner end, and a feather, e, to fit the grooves in the socket, and the spring D, the whole arranged substantially as herein described.

HUGH THOMAS.
ROBERT WALLACE.
